PORTABLE BAR

Filed Jan. 27, 1932

UNITED STATES PATENT OFFICE

WILBUR J. HEUER, OF MILWAUKEE, WISCONSIN

PORTABLE BAR

Application filed January 27, 1932. Serial No. 589,111.

My invention relates generally to portable bars, counters, etc., for general use in stores, homes, etc., where it is desired temporarily to use a counter for serving refreshments.

5 It is frequently desirable in various places of amusement and in homes to temporarily set up a counter or bar for the service of refreshments to patrons and guests, and my invention contemplates the provision of a small 10 portable bar which may readily be folded up so as to occupy a minimum amount of space when not in use and which may be quickly and easily set up and will form a rigid structure when in use.

15 It is an object of my invention to provide a portable bar in which most of the parts thereof are hingedly joined so that they may be readily folded up to form a compact package which will require small amount of storage 20 space.

A further object is to provide an improved portable bar having a bar rail which is automatically locked in its supports.

A further object is to provide a portable 25 bar which is simple in construction, may be economically manufactured, and which may be conveniently used.

Other objects will appear from the following description, reference being had to the 30 accompanying drawing, in which

Figure 1 is a perspective view of the portable bar as shown set up ready for use;

Figure 2 is a vertical sectional view thereof taken on the line 2—2 of Fig. 1;

35 Figure 3 is a rear elevation of one side of the bar showing the means for securing the shelf in place;

Figure 4 is an enlarged fragmentary perspective view showing the shelf clamping 40 means; and

Figure 5 is an end elevational view showing the bar in collapsed position.

The bar comprises a paneled front wall 10 having side walls 12 and 14 secured thereto 45 by hinges 16. The front wall 10 is sufficiently long so that the end walls 12 may be swung inwardly so as to lie in a common plane. The top is composed of a strip 18 rigidly secured to the front wall 10 and a portion 20 which is 50 secured to the portion 18 by means of a hinge

22. The end walls 12 and 14 have horizontal grooves 24 formed on their inner sides, these grooves being adapted to receive a shelf 26. The shelf 26 extends the full length of the bar and has a pair of window sash fasteners 55 28 secured thereto, these fasteners cooperating with suitably formed plates 30 secured to the end walls 12 and 14. By means of these fasteners 28, the end walls may be tightly clamped to the shelf, the shelf thus serving 60 as a rigid brace for the end walls.

A rail 32 extends through suitable holes 34 formed in rail support brackets 36. The rail support brackets 36 are secured to the front wall 10 adjacent the base thereof by means of 65 spring hinges 38. These hinges serve the two-fold purpose of slightly canting the brackets when the bar is set up as shown in Fig. 1, thereby holding the rail 32 against longitudinal sliding movement relative to 70 the brackets, and when the bar is collapsed as shown in Fig. 5, the spring hinges serve to swing the brackets 36 toward the front wall 10 and hold them in this position.

From the above description it will appear 75 that the bar may be assembled in the following manner: With the parts in the collapsed position as indicated in Fig. 5, the portion 20 of the top is swung upwardly to horizontal position, whereupon the end walls 12 and 14 80 may be swung outwardly so as to take the position in which they are shown in Fig. 2. The mounting of the hinges 16 will be such that the end walls cannot be swung outwardly beyond this position any appreciable distance. Thereafter, the shelf 26 may be slid in the grooves 24 formed in the end walls 12 and 14 to the position in which it is shown in Fig. 2, and the window sash fasteners operated readily to clamp the shelf to the end 90 walls. The rail 32 may then be passed through the openings in the brackets 36. It will be noted that the rail and the brackets 36 mutually cooperate to hold each other in the position shown in Fig. 1.

95 It will be apparent that many modifications of my invention may be made without departing from the underlying principle thereof. For example, other means may be utilized for fastening the shelf to the end walls 100

and the construction of the bar otherwise slightly altered to suit individual preferences.

It will therefore be apparent to those skilled in the art that while I have illustrated a preferred embodiment of my invention, the above and numerous other modifications may be made without departing from the spirit thereof, and I do not wish to be limited to the precise details set forth but desire to avail myself of all changes within the scope of the appended claim.

I claim:

In a portable bar, the combination of a vertical front wall, a pair of vertical side walls hinged to said front wall so as to be foldable snugly against the rear surface of said front wall, a top hinged to said front wall at a distance spaced from the upper edge of the front wall sufficiently to permit the top to be folded downwardly behind the side walls when the latter are folded inwardly behind the front wall, and means to hold said side walls in extended position comprising a removable shelf and means on the side walls to support said shelf.

In witness whereof, I hereunto subscribe my name this 25th day of January, 1932.
